UNITED STATES PATENT OFFICE.

PERCY BROWN AND FRANCIS JOHN BOSTOCK, OF HUDDERSFIELD, ENGLAND.

WORM OR LIKE MILLING MACHINE.

1,100,521.

Specification of Letters Patent. Patented June 16, 1914.

Application filed October 8, 1913. Serial No. 794,042.

To all whom it may concern:

Be it known that we, PERCY BROWN and FRANCIS JOHN Bostock, subjects of King George V of Great Britain, residing at

5 Huddersfield, in the county of York, England, have invented certain new and useful Improvements in Worm or like Milling Machines, of which the following is a specification.

10 This invention in worm milling machines relates to the means for supporting and traversing and rotating the work in front of the cutter and has for its principal object the provision of a work table of im-
15 proved construction and arrangement to take the strains and thrusts due to cutting, the slide on which the table is supported being always in compression and therefore free from lateral stresses so that it has a
20 smooth traverse and is not subject to vibration, suitable mechanism being provided in conjunction with the said table to traverse and rotate the work.

According to our invention, the work table has its face arranged at an angle of about 45°, and at the base of the inclined face there are provided openings through which the metal cuttings fall into an inclosed chamber provided with a strainer
25 so that lubricant carried down with the cuttings may be drained away and returned to the pump well for re-use. The inclined table has formed on, or secured to, one end thereof a pedestal or bracket, having
30 movable jaws each provided with a plurality of rollers which are adapted to engage the tail end of the work spindle and form a self-centering steady for same. Inclined work tables have been employed in grind-
35 ing machines and lathes, but our improvements have no reference to the tables of such machines.

The table is moved endwise to give the correct lead to the worm blank and the latter is slowly rotated in front of the cutter, by gearing which will be described.

In the drawings, Figure 1 is a vertical section through a milling machine constructed according to this invention. Fig. 50 2 is a detail plan view of a portion of the bed.

In the drawing, 1 represents the bed or framework of the machine, 2 the cutter

spindle, carried by a bracket or head 3 mounted on the bed, and 4 the guide way 55 or guide on or in which the work table 5 slides.

According to our invention, the face 6 of the work table is inclined or arranged at an angle as shown, the angle of inclination 60 in the present instance being one of forty-five degrees. The work table is arranged in front of the cutter spindle, and its face 6 is inclined downwardly and rearwardly. At the base of the inclined face of the 65 table a longitudinal recess 7 is formed, extending the length of the frame or bed, and in the bottom of this recess are openings 37 communicating with an inclosed chamber 8. The metal cuttings gravitate 70 down the inclined face of the table 5 into the recess 7 and fall through the openings in the bottom of the said recess into the chamber 8, and on to a perforated grid or strainer 9, through which any lubricant 75 which may be carried down with the cuttings drains off into a well 10 from whence it flows through a pipe 11 back to the pump well for re-use. The cuttings are removed from the chamber 8 through a door 12. 80 In various machines provision has been made for receiving the metal or like cuttings, draining the lubricant therefrom and returning such lubricant to the cutters, and no broad claim is made to any such arrangement. 85

Formed on or secured to one end of the inclined face of the table, and in this instance adjustably secured by means of a bolt 13 the head of which enters a longitudinal slot 14 in the table is a pedestal or bracket 15 having two movable jaws 16, 16, each provided with a plurality, in this instance two, of rollers 17. The rollers are adapted to engage the tail end of the work 95 spindle, which is indicated by the dotted circle 18, and to form a self-centering steady for same. The jaws 16, 16, are adjustable toward or away from one another, to accommodate spindles of different diameters, by 100 means of a screw provided with a hand wheel 19. The opposite end of the table carries the usual driving and dividing head and the chuck or holder in which the worm spindle is gripped. These forming no part of 105 our present invention are not shown.

By reason of the inclination of the table in the manner set forth the whole of the strains and thrusts due to cutting are correctly taken directly on the bed 1 on which 5 the table is supported, and better results are thereby obtained.

The correct lead is given to the worm spiral, and the latter is slowly rotated in front of the cutter in the usual manner, by 10 motion transmitted from the main driving pulley 20 of the machine through a clutch 21 and a speed gear box 22 to a shaft 23. This shaft, by means of a worm 24 and worm wheel 25 drives the shaft 26 of a 15 change speed gear, not shown, suitably designed to give a complete range of feed speeds, and said shaft 26 drives, through a second clutch, not shown, the main table shaft 27 from which the work chuck, not 20 shown, is driven by worm and worm wheel. By means of suitable change wheels, not shown, the shaft 27 also drives a lead screw 28 carried by the table, said screw working through a nut formed or carried by a fixed 25 bracket or part 29.

Any suitable construction of automatic trip gear is provided to cause the clutch between the change speed gear and the shaft 27 to be disengaged at the required times to 30 arrest the travel of the table in either direction.

Having thus described our invention,

what we claim as new and desire to secure by Letters Patent is:—

1. In a milling machine, the combination, 35 with a bed provided with a head and having a stationary horizontal guide arranged crosswise of the head and in front of it, of a vertical cutter spindle journaled in the head and arranged to the rear of the said guide, 40 and a work-table having a horizontal base surface which slides on the said guide and which has a downwardly and rearwardly inclined face for supporting the work, said face being arranged at an acute angle to the 45 said base surface.

2. In a milling machine, the combination, with a bed provided with a head and having a guide arranged in front of the head and having also a longitudinal recess arranged between the said guide and head and provided with discharge openings for chips; of a work table mounted in the said guide and provided with a downwardly and rearwardly inclined face which discharges the 50 chips into the said recess.

In testimony whereof we affix our signatures in the presence of two witnesses.

PERCY BROWN.

FRANCIS JOHN BOSTOCK.
